UNITED STATES PATENT OFFICE.

ADOLPH A. THOMAS, OF NEW YORK, N. Y.

ELECTRIC SOUND REPRODUCER.

Application filed March 10, 1926. Serial No. 93,547.

My invention is for a new and improved electric sound reproducer of simple construction and possessing a high degree of sensitivity. The instrument of my invention may be used for recording, transmitting and reproducing sound-wave energy, but for brevity I shall refer to it simply as a sound reproducer without thereby intending any restriction. At the present time my invention has special advantages as an electric phonograph reproducer, particularly for use on records having a microscopic groove of several hundred threads to the inch, where the vibrations of the needle point are too delicate for satisfactory mechanical reproduction.

It has been proposed to make phonograph records with a spiral track so fine and operating at such low speed that a twelve-inch record will play for an hour and even longer. Mechanical reproduction from such records is obviously out of the question. A record groove having several hundred threads to the inch is too delicate for a needle point connected to a stiff diaphragm, as in the old phonograph sound boxes familiar to all. Electric reproducers of the microphone type (also using a diaphragm) have been used on phonograph records of the old style—that is, records having about 100 lines to the inch, where the groove is comparatively deep and wide. While a groove like that is capable of actuating a needle against the high tension and resistance of a stiff diaphragm, a very different problem arises in the case of a record having from 300 to 500 threads to the inch and of corresponding fineness in width and depth. A groove of such microscopic dimensions will not stand the wear and tear inevitably attending the use of a reproducer in which the needle operates a diaphragm, whether the latter be purely mechanical or part of an electrical reproducing mechanism.

It is the purpose of this invention to provide an electric reproducer especially adapted for phonographic use, in which the vibrations of the needle point are transmitted in greatly amplified ratio to a pivoted coil or to a member arranged to oscillate in a magnetic field. In the preferred form of the invention, the inner end of the needle arm is connected to the pivot shaft of the coil by a thread or fiber, which eliminates all lost motion. Suitably arranged resilient means

normally hold the coil and needle arm in predetermined position and always maintain the connecting thread taut. These resilient means, the tension of which is adjusted to the right degree, offer practically the only resistance to a needle point in the record groove, and this resistance may be very small, depending upon the physical characteristics of the groove. The coil is not attached to, or connected with, a movable iron core or armature. In other words, the coil is coreless and therefore it can be made so light as to have no appreciable inertia in its oscillations. Nor is there any magnetic drag or load imposed upon the needle arm by the electromagnetic reproducing mechanism. Hence, the needle arm is free to respond correctly to the minutest vibrations of the needle point, which may be as small as (and even smaller than) a thousandth of an inch. The mechanical amplification between the needle point and the sides of the pivoted coil is such that the smallest needle vibrations oscillate the coil to cut the magnetic flux and thereby generate current impulses, which are electrically amplified to operate a loudspeaker or other suitable device.

In order to explain my invention fully and clearly, so that those skilled in the art may understand and practise the same, I shall refer to the accompanying drawings in which I have illustrated a preferred embodiment of the invention when used as a phonograph reproducer. In these drawings,

Fig. 1 shows an inside face view of an electric phonograph reproducer constructed in accordance with my invention, certain parts being for clearness cut away on the broken line 1—1 of Fig. 2;

Fig. 2 represents a sectional view taken approximately on line 2—2 of Fig. 1;

Fig. 3 is a transverse cross-section on the broken line 3—3 of Fig. 1;

Fig. 4 is a similar cross-section on line 4—4 of Fig. 1;

Fig. 5 illustrates the coil-supporting frame in detached perspective view; and

Fig. 6 indicates diagrammatically the amplifying transmission between the needle arm and the pivoted coil.

Before proceeding with a detailed description of these figures, I want to explain that the various parts have been purposely drawn in grossly exaggerated proportions, so as to make the drawings clear and easy to read.

The actual instrument is made very small and compact; indeed, it need be no bigger than an ordinary watch.

The different parts of the mechanism are mounted in a casing indicated as a whole by C and constructed of suitable non-magnetic material, such as aluminum, brass and the like. In the present instance, the casing consists of a back plate 1, a cylindrical body section 2, and a front plate or cover 3. These parts are separately secured together by screws 4 or otherwise.

If the case is made of moldable material, like bakelite for instance, the parts 1 and 2 may be cast as a single cup-shaped member. The back plate 1 has a hub 5 adapted to fit tightly over a tubular supporting arm 6, which is supposed to be so mounted that the reproducer travels over a record in playing position. Suitable means, such as a set-screw 7 on arm 6 and a bayonet slot 8 on hub 5, holds the casing in proper position on the supporting arm.

In casing C is mounted a magnet M, here shown as a permanent steel magnet of circular form to fit closely around the periphery of the casing. This permits the use of a magnet of maximum length in a small space. Manifestly, instead of a permanent magnet, any other practical means may be employed to establish a normally constant magnetic field. In the present construction, it is convenient to attach the magnet to the back plate 1, as by screws 9 or otherwise. The polar ends of the magnet are bent forwardly, as shown at 10, and to these polar ends are rigidly secured pole pieces 11 by screws 12. The pole pieces 11 are usually made of soft iron or other material of high magnetic permeability, and their opposing ends terminate in extensions 13, as best shown in Fig. 3.

In the airgap 14 formed between the polar extension 13 oscillates a small coil 15 mounted on a pivoted shaft 16. There is no iron core or other heavy mass movable with the coil, so that the inertia of this oscillatory unit can be made so low as to be practically negligible. The arc-shaped polar extensions 13 provide a substantially uniform field across the airgap, as will be understood from Fig. 3, and the width of this uniform field is sufficient to include the maximum oscillations of coil 15. This feature of a coil free from a movable iron mass and mounted to oscillate without appreciable inertia in a practically uniform magnetic field is of considerable importance, for it adds to the sensitiveness and accuracy of the instrument. In the preferred form of my invention, the coil is supported on the magnet itself, so that the coil and magnet can be properly assembled and adjusted before insertion into the casing. For this purpose, I provide a non-magnetic frame indicated

as a whole by F. This frame is rectangular in form, and the side bars 17 thereof are recessed or offset at 18 to receive the pole pieces 11, to which the entire frame (with all the parts it carries) is secured by screws 19. The coil shaft 16 is journalled in adjustable bearings 20 in the upper and lower cross-bars 21 of frame F. These bearings are preferably jewel bearings or of equally practical construction. The offset recesses 18 in frame F bring coil 15 into central alignment in the airgap 14, as may be seen from Fig. 3. A light coil spring 22 is secured at one end to the coil shaft 16 and at the other end to a pin or lug 23 on frame F. The purpose of spring 22 is not only to hold coil 15 in normal predetermined position, but also to positively actuate the coil in one direction, as will presently be explained. The normal tension of spring 22 may be regulated by any suitable means, as by passing its outer end adjustably through a slot in lug 23 and securing the adjusted end in position.

A needle arm 24 is pivoted to casing C in any practical way. In the drawings I have shown a pair of lugs 25 projecting from the lower end of the casing, and in these lugs are mounted pivot bearings 26 between which the needle arm is supported for vibratory movement. The lower end of needle arm 24 is in the form of a needle holder 27. A slot 28 in the body section 2 of the casing permits the needle arm to extend freely into the casing. The inner end of needle arm 24 is connected to the coil shaft 16 in any practical way. At the present time I prefer a filar connection 29 in the form of a thread, fiber, fine wire, and the like. For the sake of brevity, I shall refer to the connection 29 as a thread, it being understood that I am using this term in its broadest possible sense. The thread 29 is fastened at one end to the needle arm 24, as indicated at 30, and the other end of the thread is attached to shaft 16 of the coil. This is perhaps most conveniently done by providing a very small pulley 31 on shaft 16. The thread is fastened to the pulley, wound around it a few times, and the other end is then connected to the needle arm. There is thus no lost motion between coil 15 and needle arm 24, and thread 29 is not affected by temperature conditions.

A resilient wire 32 (a thin piano wire will do) is stretched transversely across the casing and is connected to the needle arm—as by passing in a tight fit through a small hole in the arm. The ends of the tensioned wire 32 are secured to adjustable anchor pieces 33 mounted in the body section 2 of the casing. The normal tension of spring 22 and wire 32 is such that normally the coil 15 and needle arm 24 are held in predeter-

mined position, as illustrated in Figs. 2 and 3. That is to say, the normal tendency of spring 22 and wire 32 is to oppose each other, the wire 32 normally tending to pull the needle arm away from the magnet (and thus to rotate the coil clockwise, as viewed in Fig. 3), and the coil spring 22 normally tending to turn the coil in the reverse direction. Consequently, the thread 29 is always under tension, and no lost motion is possible between the needle arm 24 and the oscillating coil 15. This is important, because the vibrations of the needle arm, even at maximum amplitude, are very small, and they must be transmitted without loss to the coil.

The operation of the mechanism above described will now be understood by those skilled in the art, but I may briefly summarize it in a few sentences: As the needle arm vibrates during the playing of a record, the inner end of the arm moves toward and away from the magnet. Whenever the arm moves away from the magnet, it pulls the thread 29 and this turns the coil 15 (clockwise as viewed in Fig. 3) out of its normal position, thereby causing it to cut the magnetic lines of force and generate a current impulse. This movement of the needle arm and coil is against the tension of spring 22, which is thus slightly wound up. Now, as the inner end of the needle arm moves toward the magnet, the tension on thread 29 is relaxed and the tensioned coil spring 22 immediately turns the coil in the opposite direction as far as the position of the needle arm permits, thereby generating another current impulse. It will thus be seen that the needle arm positively actuates the oscillating coil 15 in one direction, and the spring 22 positively actuates the coil in the opposite direction. These oscillations of the coil generate current impulses which are electrical representations of the needle vibrations. Attention is called to the fact that the oscillations of the coil are not damped or impeded by mechanical inertia or magnetic drag, since there is no magnetic mass movable with the coil. I might explain that, when I refer to the coil 15 as coreless, I mean that it is not mounted on, or connected to, or otherwise provided with, an iron core or armature or other heavy mass that moves with the coil. I do not mean to exclude, however, the use of a stationary piece of iron between the pole pieces and within the space defined by the movements of the coil, since such a fixed magnetic piece would not add to the inertia of the coil and would be employed merely to concentrate the magnetic lines.

I have not deemed it necessary to show or describe any circuit connections for coil 15, because such connections form no part

of my invention, and also because it is well understood by those familiar with this art how to utilize electric current impulses to operate a loudspeaker or other acoustic device. It is sufficient for this case that I have shown a pair of insulated terminals or binding posts 34 mounted on the back plate 1 of the casing and to which the ends of coil 15 are connected. Conductors 35 lead from the binding posts 34 through the hollow arm 6 to a suitable amplifying system for properly amplifying the feeble current impulses generated by the oscillating coil 15. Various amplifying circuits are well known in the art.

Attention is directed to the fact that the minute vibrations of the needle point are mechanically transmitted to the coil in greatly amplified ratio: First, there is the amplified movement of the inner end of the needle arm in relation to the movements of the needle point. This amplifying ratio may be from 3:1 to 5:1, depending upon the relative lengths of the needle arm on opposite sides of the pivot. Then, there is the multiplying connection between the needle arm and the coil. A very short pull on the thread 29 in one direction, or a very small turn of the coil shaft 16 by the spring 22 in the other direction, swings the two sides of the coil through an arc that cuts the magnetic flux even when the angular movement of the coil is a minimum. This will easily be understood from the diagram in Fig. 6. Let us imagine that the line 36 represents the normal position of coil 15, and that the point 37 represents the axis of the coil. Now, let us suppose that the needle arm pulls the thread an amount indicated by the line 38, so that the coil turns into the position shown by the heavy line 39. In other words, the coil has moved through an angle 40, which is relatively very small, but the opposite sides *a* and *b* of the coil have opened to the magnetic flux a wide area represented by (or proportional to) the line 41, which is the effective coil area at that moment. Roughly speaking, therefore, the ratio of line 41 to line 38 represents the multiplying connection between the needle arm 24 and the coil 15. In the present instance, this multiplying connection is about 1:20, as measured in Fig. 6, and that may be taken as a fair illustration, without intending it as a restriction. The shortest possible pull on thread 29, as when the needle point vibrates with an amplitude of less than a thousandth of an inch, is sufficient to move the coil 15 to cut magnetic lines of force. It goes without saying that the lines in Fig. 6 have been purposely exaggerated in relative proportions to make the figure clear. In the actual instrument, the angular movements of the coil are very small, indeed. Assuming the amplifying ratio between the needle point and the inner

end of the needle arm to be about 1:3 (a very practical ratio), and further assuming the multiplying connection between the needle arm and the sides of the coil to be about 1:20, it is clear that the needle vibrations are transmitted to the coil in an amplified ratio of about 1:60.

It is advantageous to hold the coil 15 normally in neutral or zero position, as shown in Fig. 3, where practically no lines of force pass through it, because under those conditions the oscillatory movements of the coil give maximum response. That is so for the reason that the value of an induced electro-motive force is proportional to the rate at which magnetic lines of force are cut by the moving conductor, and the lines of force are cut most rapidly when the curve of magnetic flux passes through zero.

It should be observed that the coil 15 and magnet M exert no magnetic drag on the needle arm, thus leaving the latter free to be vibrated in strict accordance with the undulatory track on the record. The spring 22 and wire 32, which always tend to balance each other, offer just enough resistance to the movement of the needle point to impose the proper load on the needle arm. Since the coil 15 is made very small and exceedingly light, its inertia may be considered negligible. This increases the sensitivity and precision of the instrument.

In playing a phonograph record having several hundred lines to the inch, the pressure of the needle point in the record groove should be much less than in the case of the old-type records having comparatively deep and thick-walled grooves. If the normal weight of the reproducer on account of magnet M (the only heavy part it contains) is greater than it should be to obtain the best results from a finely grooved record, the effective pressure of the needle point can be regulated as desired by a counteracting weight on arm 6, or by any other practical means. The exact pressure with which the needle point should track the record groove for the most satisfactory reproduction is a matter of trial and experiment.

In the broader aspect of my invention, the vibratory coil 15 may be connected to an acoustic diaphragm set in motion by sound waves, so that the instrument will operate as a telephone transmitter, particularly useful for broadcasting. The operation of coil 15 with a diaphragm is the same as above described. Also, it will be clear that when current impulses are passed through coil 15, the same will oscillate in the magnetic airgap and cause vibration of the needle arm 24 or of a diaphragm connected to the coil. In that event, the instrument can be used as a phonographic recorder or as a telephone receiver. All these and other uses are within the scope of my invention. The particular

instrument herein shown and described is merely an illustrative embodiment of my invention, and is not to be regarded as a restriction or limitation thereof.

What I claim as my invention is:

1. In an electric phonograph reproducer, means for establishing a magnetic field, a coreless coil mounted centrally on a rotary shaft to oscillate in said field, a needle arm pivoted near one end so that the needle vibrations are transmitted to the other end in amplified ratio, and an amplifying connection between said other end of the arm and said shaft. 70

2. An electric phonograph reproducer comprising a casing, a magnet structure mounted in said casing and having an air-gap, a non-magnetic frame secured to said structure, a coil pivotally mounted on said frame so as to oscillate in said airgap, and a needle arm carried by said casing for oscillating said coil. 80

3. An electric phonograph reproducer having a needle arm, a coil mounted on a rotary shaft so as to oscillate in a magnetic field, and connecting means between said arm and said shaft for transmitting the movements of the arm to the sides of said coil in amplified ratio. 90

4. An electric phonograph reproducer having a centrally pivoted coil arranged to oscillate in a magnetic field, and connections whereby the needle vibrations are mechanically transmitted to the flux-cutting sides of said coil in amplified ratio, said connections including a taut filar member adapted to prevent lost motion. 95

5. In an electric acoustic device, a centrally pivoted coil mounted to oscillate in a magnetic field, an acoustically operated member, a flexible connection between said member and said coil for positively actuating the coil in one direction only, and means independent of said member for positively actuating said coil in the other direction, 100 said means being controlled by the movements of said member. 110

6. An electric sound transmitter including a vibratory member, a coil mounted to oscillate about a central shaft in a magnetic field 115 to cut the lines of force, a filar connection between said member and said shaft to swing said coil in one direction, and a spring for holding said filar connection under tension and swinging said coil in the opposite direction. 120

7. An electric phonograph reproducer having a coil mounted centrally on a rotary shaft so as to oscillate in a magnetic field, a needle arm, a filar connection between said arm and said shaft for positively rotating the latter in one direction, a spring connected to said shaft for rotating the same in the reverse direction, and resilient means acting in opposition to said spring for hold- 125 130

ing the coil and needle arm in normal predetermined position.

8. In an electric phonograph reproducer, a vibratory needle arm, a pivoted electro-magnetic member mounted independently of said arm, a flexible connection between said arm and said member for causing the arm to actuate said member positively in one direction, spring means for positively actuating said member in the opposite direction, and resilient means connected to said arm and adapted to cooperate with said spring means for holding said arm and said member in normal predetermined position.

9. An electric acoustic instrument comprising a pivoted shaft, a coil fixed centrally on said shaft, means for establishing a magnetic field in which said coil is mounted to cut the lines of force, an acoustically actuated member, a filar connection wound around said shaft and attached to said member, so that movement of said member away from said shaft produces rotation of the shaft and coil in one direction, a spring connected to said shaft for rotating the same in the opposite direction when said member moves toward the shaft, whereby the vibrations of said member produce oscillation of said coil with practically no lost motion and with amplified effect to generate current impulses in the circuit of said coil, said coil being also adapted to oscillate when current impulses are sent therethrough to actuate said member.

10. In an electric phonograph reproducer, a needle arm, electromagnetic mechanism including a centrally pivoted element mounted independently of said arm and operatively connected thereto, and a pair of oppositely acting resilient members for holding said arm and said element in normal predetermined position, one of said members being connected to said arm and the other member being connected to said element.

11. An electric sound transmitted comprising a magnet having an airgap, a non-magnetic frame secured to said magnet, a coil pivoted on said frame for oscillatory movement in the magnetic airgap, and a vibratory acoustic member connected to said coil in amplified transmission ratio.

12. An electric phonograph reproducer comprising a permanent magnet, pole pieces secured to said magnet to provide an airgap, a non-magnetic frame mounted on said pole pieces, a coil pivoted on said frame for oscillatory movement in the magnetic airgap, and a needle arm for actuating said coil.

13. In an electric phonograph reproducer having a magnet, a unitary structure adapted to be mounted as a single member on said

magnet, said unitary structure comprising a pair of pole pieces adapted to be directly attached to the polar ends of said magnet, a non-magnetic frame rigidly connected to said pole pieces, and a coil centrally pivoted on said frame so as to oscillate between said pole pieces.

14. In an electric phonograph reproducer, a casing in which is mounted a pivoted coil for oscillation in a magnetic airgap, a needle arm connected to said coil by a flexible member, a spring connected to said coil, and a tensioned wire stretched transversely across said casing and at the center engaging said arm, said spring and wire acting in opposite directions to normally hold said coil and said arm in predetermined position.

15. An electric phonograph reproducer comprising a magnet having an airgap, a non-magnetic frame, a shaft journaled in said frame, a coil fixed to said shaft so as to oscillate in said airgap, a helical spring connected at one end to said shaft and at the other end to said frame and at the magnetic airgap, a needle arm, a flexible connection between said shaft and the inner end of said needle arm, and a resilient tension member connected to said needle arm for holding the same in normal predetermined position.

16. An electric acoustic device having a coil mounted centrally on a rotary shaft so as to oscillate in a magnetic field, a vibratory acoustic member, a thread or fine wire for operatively connecting said shaft and said member, and resilient means for normally holding said coil in predetermined position.

17. In an electric phonograph reproducer, a casing adapted to be mounted on a suitable support, a magnet secured to a wall of said casing in such position that the magnetic airgap is near one end of the casing, a needle arm pivoted near one end to said casing at a point diametrically opposite said airgap, so that the needle vibrations are transmitted to the inner end of said arm in amplified ratio, a coreless coil pivoted to oscillate in said airgap, and an amplifying connection between said coil and the inner end of said needle arm.

18. An electric acoustic device having a coil mounted to oscillate on a rotary shaft in a magnetic field, a vibratory acoustic member, a filar connection between said member and the shaft of said coil for oscillating the coil in one direction, and means for oscillating the coil in the reverse direction.

ADOLPH A. THOMAS.
